(57) **CLAIM**

The ornamental design for a lottery ticket dispenser array with stacked lottery ticket modules, as shown and described.

DESCRIPTION

FIG. 1 is a front view of a lottery ticket dispenser array with stacked lottery ticket modules according to the present design;

FIG. 2 is a back view of the lottery ticket dispenser array of FIG. 1;

FIG. 3 is a right side view of the lottery ticket dispenser array of FIG. 1;

FIG. 4 is a left side view of the lottery ticket dispenser array of FIG. 1;

FIG. 5 is a top view of the lottery ticket dispenser array of FIG. 1;

FIG. 6 is a bottom view of the lottery ticket dispenser array of FIG. 1;

FIG. 7 is a front and right side perspective view of the lottery ticket dispenser array of FIG. 1;

FIG. 8 is a back and right side perspective view of the lottery ticket dispenser array of FIG. 1;

FIG. 9 is front view of the lottery ticket dispenser array of FIG. 1 within a cabinet; and,

FIG. 10 is front and right side perspective view of the lottery ticket dispenser array of FIG. 1 within a cabinet.

The claimed design comprises the elements shown in solid lines, the elements shown in dotted lines forming no part of the claimed design.

1 Claim, 10 Drawing Sheets
